(57) CLAIM

The ornamental design for a T-shirt, as shown and described.

DESCRIPTION

The sole FIGURE is a plan view of a T-shirt showing my new design.

The dashed broken line outline of the T-shirt shows environmental structure in which the design resides.

The dashed broken lines inside the square illustrate portions of the design which forms no part of the claim.

The claim is directed to the solid lines and all surfaces adjacent to both solid and broken lines.
